CLAIM

The ornamental design for an electrical connector for towing vehicles, as shown and described.

DESCRIPTION

FIG. 1 is a front perspective view of the electrical connector for towing vehicles of the present invention with the broken lines in the drawing depicting environmental subject matter only and forming no part of the claimed design;

FIG. 2 is a top front perspective view of the electrical connector for towing vehicles of the present invention with the broken lines in the drawing depicting environmental subject matter only and forming no part of the claimed design;

FIG. 3 is a bottom left rear perspective view of the electrical connector for towing vehicles of the present invention with the broken lines in the drawing depicting environmental subject matter only and forming no part of the claimed design;

FIG. 4 is a front elevational view of the electrical connector for towing vehicles of the present invention with the broken lines in the drawing depicting environmental subject matter only and forming no part of the claimed design;

FIG. 5 is a left side elevational view of the electrical connector for towing vehicles of the present invention with the broken lines in the drawing depicting environmental subject matter only and forming no part of the claimed design;

FIG. 6 is a right side elevational view of the electrical connector for towing vehicles of the present invention with the broken lines in the drawing depicting environmental subject matter only and forming no part of the claimed design;

FIG. 7 is a top plan view of the electrical connector for towing vehicles of the present invention with the broken lines in the drawing depicting environmental subject matter only and forming no part of the claimed design;

FIG. 8 is a bottom plan view of the electrical connector for towing vehicles of the present invention with the broken lines in the drawing depicting environmental subject matter only and forming no part of the claimed design; and,

FIG. 9 is a rear elevational view of the electrical connector for towing vehicles of the present invention with the broken lines in the drawing depicting environmental subject matter only and forming no part of the claimed design.
